UNITED STATES PATENT OFFICE.

FREDERICK W. EAMES, OF WATERTOWN, NEW YORK.

VACUUM-BRAKE APPARATUS.

SPECIFICATION forming part of Letters Patent No. 228,740, dated June 15, 1880.

Application filed November 22, 1879.

To all whom it may concern:

Be it known that I, FREDERICK W. EAMES, of Watertown, in the county of Jefferson and State of New York, have invented certain new and useful Improvements in Vacuum-Brake Apparatus, (Case A;) and I do hereby declare the following to be a full, clear, and exact description of the invention, such as will enable others skilled in the art to which it appertains to make and use the same, reference being had to the accompanying drawings, and to letters of reference marked thereon, which form a part of this specification, in which—

Figure 1 represents a side elevation of my improved braking apparatus as applied to a locomotive and its tender, the two latter being partially illustrated by dotted lines. Fig. 2 represents a plan of the under side of the same, portions of the locomotive and tender being shown in dotted lines. Fig. 3 illustrates my improved method of storing vacuum-power by the use of an additional tank having free communication with the operating-cylinder. Fig. 4 represents a modification of the devices shown in Fig. 3, in which but a single air-pipe is used instead of two.

My invention relates to improvements in apparatus for operating the brakes of railroad-cars, more especially to that class of brakes in which the natural pressure of the atmosphere, as opposed to a vacuum, is employed to operate the mechanism, the vacuum for this purpose being formed by means of an air-ejector, pump, or other exhaust operated by the force of steam.

My improvement consists in an improved vacuum-brake apparatus, wherein the ejector can be made to operate continuously, so as to be constantly at work in creating and maintaining a vacuum, or so that it will cease to operate when a given amount of vacuum-power has been stored up, and again begin to operate when a given minimum is reached.

It also consists in an improved construction and mode of applying a vacuum-brake apparatus, by means of which the brakes can be more quickly and readily applied and released and the vacuum-power automatically maintained.

It also consists in combining an air-ejector, automatic or otherwise, and an auxiliary vacuum-chamber with the vacuum or operating

cylinder, whereby the brakes are not only more speedily applied, but a reserve power maintained ready for use should the steam in the boiler be too low to apply them effectually.

Referring to the parts by letters, which are the same in all the figures, A represents an air-ejector operated by steam from the steam-chest of the boiler of the locomotive, and which is conducted to it through a suitable pipe, a. This ejector apparatus is employed to create a vacuum in the air-pipes, which extend throughout the length of the train and connect with the brake-cylinders attached to each carriage.

Atmospheric pressure, as opposed to a vacuum, being the power employed to apply or release the brakes, and said power being created by the steam in the boiler, it will be obvious that so long as there is sufficient steam-power in the locomotive to move the train there will be sufficient power to stop its momentum. Moreover, the vacuum-power may be stored up when there is sufficient steam for the purpose, and afterward utilized to apply the brakes, even should the steam in the locomotive-boiler fail in an emergency.

B B' are the air-pipes, which are attached to the several carriages or cars of the train. These pipes are connected between the carriages by short flexible hose-pipes and couplings of any known and suitable construction. The air-pipes are also connected, by means of branch pipes b b', with the brake-cylinder or vacuum-chambers C, secured to each carriage or member of the train. The brake-cylinders or vacuum-chambers may be constructed in different ways, but however constructed the piston and piston-rod are arranged to operate either by the formation or the destruction of a vacuum in the connecting air-pipes.

In Figs. 1 and 2 of the drawings the brake-cylinder is represented by the letter C, and in it a vacuum is maintained on both sides of the piston to keep the brakes off the wheels. By destroying the vacuum on one side of the piston the brakes are immediately applied through the brake-lever D, which for this purpose is connected with the piston-rod.

To illustrate the operation of this apparatus, I will suppose the ejector A to be in operation, drawing the air from the pipe B and cylinder C, and there being a valve in the piston-

head suitably constructed for that purpose, it will also draw the air from the cylinder on both sides of the piston, and through the branch pipe b' it will also draw the air from the pipe B' , creating a vacuum in both pipes and cylinder, and the operation of the cylinder being automatic the vacuum will be preserved and the brakes kept from the wheels until it is desired to apply them.

- 10 To apply the brakes the valves of the ejector are shifted so as to close communication between the pipe B and open it between B' and the ejector. At the same time another valve is opened in the pipe B , to admit air into the pipe and destroy the vacuum. The air immediately passes by the pipe B through the branch b into one end of the cylinder C , thereby moving the piston-rod. By again reversing the position of the valves of the ejector 15 communication is shut off between the pipe B and the external air and opened between it and the ejector. The operation of the latter will then draw the air from B and cylinder C , and create a vacuum therein, as before described, to release the brakes.

In Fig. 3 of the drawings is illustrated the method of storing vacuum-power by the use of an additional tank having free communication with the operating-cylinder. In this, as 20 in the former figures, C is the operating-cylinder; B and B' the air-pipes connected with the ejector, as in Fig. 1. b is a branch pipe, connecting pipe B with the operating-cylinder C , and b' another branch pipe, which connects 25 the operating-cylinder C with the auxiliary vacuum-chamber C' , and also connects both of these vessels with the air-pipe B' .

The operation is the same as before described, the only difference being that when 30 the ejector is withdrawing the air from the pipe B it also withdraws it from the vacuum-chamber C' through pipe b' , and thereby creates additional vacuum-power, causing the apparatus to operate quickly in applying the 35 brakes.

It will be seen that the apparatus described has two lines of air-pipe, and I prefer to use 40 two lines; but, if preferred, a single pipe may be used, as illustrated by the diagram, Fig. 4, 45 in which C is the operating-cylinder; C' , the auxiliary vacuum-chamber, and B the air-pipe connected with the ejector apparatus and with the cylinder C by means of the branch pipe b , but not connected directly with the auxiliary vacuum-chamber C' , said chamber 55 being only connected with the end of the operating-cylinder opposite to the pipe, the connection between the cylinder and reservoir being by a small pipe, b' .

50 In this case the air is withdrawn from the auxiliary vacuum-chamber C' through the valve in the piston-head. In all other respects the operation of this single-pipe automatic brake is the same as the double-pipe apparatus before described.

These devices are all operated from the

locomotive-engine, the braking of the train being under the entire control of the engineer and driver. The brakes, however, may be applied from any point of the train by pulling 70 open valves which communicate with the external air, said valves being attached to the several brake-cylinders C , or to the air-pipe B , as it enters the cylinder, as shown at P in Figs. 1, 2, and 3 of the drawings, suitable 75 cords or levers for this purpose being led to convenient positions in the carriages.

By means of the additional lever I on the tender and the connecting-rods i , the brakes of the locomotive are operated by means of the 80 brake cylinder and piston pertaining to the tender, no brake-cylinders being required upon the locomotive. It will also be seen, on reference to Fig. 1 of the drawings, that the toggles for operating the locomotive-brakes 85 are arranged on the under side or beneath the brake-shoes, so that when released from the pressure of the levers the brakes will drop loose from the wheels by their own gravity.

These locomotive-brakes are of very simple 90 and economical construction and completely effective in operation.

The air-ejector, used in connection with the air-pipes for creating the vacuum, may be of any suitable and known construction for maintaining a vacuum in them and the operating-cylinders; but I prefer to use the improved automatic ejector for which I have prepared and have herewith filed an application for Letters Patent, and therefore do not deem it 95 necessary to describe it more particularly, especially as its special construction forms no part of this patent; and so with the valve P for the admission of air into the operating-cylinder to apply the brakes from the cars direct, it also may be made of any known construction suitable for the purpose.

I am aware that the power of a vacuum as opposed to atmospheric pressure has been employed in the operation of railway-brakes before my present invention, and I do not therefore wish to be understood as here claiming the principle of a vacuum-brake, either when the brakes are applied by the creation or destruction of a vacuum in the air-pipes and cylinders, but

What I claim, and desire to secure by Letters Patent, is—

1. The braking apparatus, constructed as herein described, consisting of an air-ejector 120 connected with two lines of air-pipes, arranged to operate in connection with the vacuum or operating cylinders in such manner that while one set of pipes is employed to destroy the vacuum on one side of the piston or diaphragm by the movement of which the brakes are applied, the air is being withdrawn and the vacuum enforced on the other side of the piston by the other set of pipes, substantially as set forth.

2. The combination of the air-ejector A , the 125 double line of pipes B B' , cylinder C , and branch pipes b b' , substantially as set forth.

3. In combination with air-ejector A, a double line of pipes, B B', each independently communicating therewith, vacuum or operating cylinder C, and air-valve P, for the purpose set forth.
4. In combination with the vacuum chamber or cylinder C and air-pipe B, an auxiliary vacuum-chamber C', constructed and arranged as and for the purpose set forth.
5. In combination with the vacuum-cylinder C and air-pipes B B', each independently communicating with the air-ejector, an auxiliary vacuum-chamber, C', for the purpose set forth.
6. In combination with air-ejector A, pipe
- B, and cylinder C, constructed substantially as described, an auxiliary vacuum-chamber, C', substantially as and for the purposes set forth.
7. In combination with air-ejector A, pipes B B', each independently communicating therewith, and cylinder C, an auxiliary vacuum-chamber, C', substantially as and for the purposes set forth.

In testimony that I claim the foregoing I have hereunto set my hand.

FRED. W. EAMES.
